MULTIPLE LOOPER MEANS FOR SEWING MACHINES

Anton Kiernan, Elizabeth, N. J., assignor to Emil Prazak, Elizabeth, N. J.

Application April 22, 1939, Serial No. 269,436

5 Claims. (Cl. 112—218)

This invention relates to improvements in sewing machines of the type adapted to simultaneously produce a multiplicity of spaced lines or runs of stitching of chain stitch formation; and the invention has reference, more particularly, to an improved construction of multiple looper means for cooperation with the gang of sewing needles included in the stitch forming mechanism of such type of sewing machine.

10 In the construction of sewing machines of the kind mentioned, difficulty has been experienced in mounting and maintaining the plurality of looper hooks in required spaced relation, particularly where it is desired to simultaneously produce a multiplicity of lines or runs of stitching in closely spaced relation, as, e. g., at relative spacing up to approximately one-sixteenth of an inch apart. Under such circumstances, the looper hooks should be properly disposed in correspondence to 15 the spacing of the gang of sewing needles operative to produce the desired closely spaced lines or runs of stitching, and should be themselves spaced in relation one to another so as to provide and maintain intervening clearance for the threads delivered by the needles and looped to the operation of the looper hooks; and, in addition to this, the looper hooks should be individually secure against displacement or shifting out of operative spaced relation one to another. It has been attempted to meet these requirements by providing 20 the looper hooks with round butt shanks for engagement in a perforate carrier block to which the same are attempted to be secured by set screws. Such arrangement, however, has not 25 proven satisfactory, since torsional stresses developed in the operation of the looper hooks tends to twist the same out of place, even though the set screws serving the same appear to remain fairly tight.

Having these things in view, it is an object of 30 this invention to provide, in combination, a novel construction of looper carrier block and a novel construction and form of looper butt shank cooperative therewith; all to the end that not only close relative spacing adjustment of the looper hooks is easily attained, but also so that once the looper hooks are mounted in and locked to the carrier block, tendency to loosening or shifting or torsional displacement thereof is most strongly resisted and substantially avoided.

Other objects of this invention, not at this time more particularly enumerated, will be understood from the following detailed description of the same.

55 An illustrative embodiment of this invention is

shown in the accompanying drawing, in which:

Fig. 1 is a top plan view of the assembled carrier block and looper hooks made according to this invention, the same being shown on a scale approximating twice the actual size thereof; Fig. 2 is a front elevation of the same; Fig. 3 is an end elevation of the same; Fig. 4 is a longitudinal vertical sectional view, taken on line 4—4 in Fig. 1; and Fig. 5 is a transverse sectional view, taken on line 5—5 in Fig. 4.

Fig. 6 is a schematic sectional view of the novel looper hook means as operatively cooperating with the sewing needles in the production of runs of chain stitching; and Fig. 7 is a fragmentary plan view of the kind of spaced lines or runs of stitching produced by the sewing mechanism equipped with the novel looper hook means of this invention.

Similar characters of reference are employed in the above described views, to indicate corresponding parts.

Referring to the drawing, the reference character 10 indicates the body of a carrier block, the same having in its lower portion a longitudinally extending bore 11 to receive the shaft or like means (not shown) by which said carrier block is operatively mounted in connection with any well known means (not shown) for imparting thereto, and to the looper hooks carried thereby, properly timed operative oscillation in cooperation with the reciprocated swing needle means of the machine.

Indenting the front side of said carrier block 10, above the bore 11 thereof, is a horizontal outwardly open socket channel 12. Formed in the bottom surface of said socket channel, to extend transversely across the same, are a series of suitably spaced upwardly open seating grooves 13 of substantially semi-circular cross-sectional shape. The top surface of said socket channel defines a flat seating surface 14 disposed in horizontal plane spaced above and in opposition to said seating grooves 13.

The looper devices comprise the usual bodies 15 which terminate at their outer end portions in downwardly directed looper hooks 16 of suitable shape. Formed integrally with the rearward end portions of the looper bodies 15 are butt shank portions 17 disposed to extend longitudinally therefrom. The top surfaces of said butt shank portions 17 are downwardly offset relative to the top surfaces of the looper bodies 15, thus providing intermediate stop shoulders 18. Said top surfaces of said butt shank portion 17 define flat faces 19 disposed in horizontal plane. The under

surfaces of said butt shank portions are of transversely convex or half round cross-sectional shape to provide rocking seating portions 20 conforming to and receivable in the seating grooves 13 of the 5 socket channel 12 provided in the carrier block 10.

To assemble the looper devices in operative affixed relation to the carrier block 10, and in relatively spaced and accurately positioned relation one to another, the butt shank portions 17 are 10 inserted endwise into and across the socket channel 12, so that the rounded underside seating portions 20 thereof are respectively engaged in corresponding seating grooves 13 at the bottom of said socket channel 12, while the top side flat 15 faces 19 are opposed to the flat seating surface 14 bounding the top of said socket channel 12. The butt shank portions 17 are thus entered until the stop shoulders 18 abut the front face of the carrier block 10, whereby the operative projecting distance of the looper devices from the latter is 20 determined.

Each looper device, as thus entered in the socket channel 12 of the carrier block, is so fitted thereto that the top side flat face 19 thereof 25 bears against the flat seating surface 14 so as to hold the looper device against twisting or turning displacement. If, as initially entered in the socket channel 12 of the carrier block, any particular looper device is canted to one side or the 30 other of a desired perpendicular position at which its looper hook 16 is required to be disposed, correction of such condition by adjustment of the looper device may be easily accomplished by withdrawing the butt shank portion and stoning 35 or filing the top side flat face 19 to trim the same so as to assure, on re-insertion of the butt shank portion into the carrier block, the proper desired perpendicular disposition of the looper device. To permit of such adjustment the 40 rounded seat portion 20 of the butt shank portion 17 will turn or rock relative to the seating groove 13 engaged thereby. When the required perpendicular alignment and relative spacing of the assembled looper devices is attained by the 45 described fitting adjustment of the latter to the carrier block 10, the butt shank portions may be suitably locked against outward displacement or withdrawal from the carrier block.

The means for locking the looper devices 50 against outward displacement or withdrawal from the carrier block 10 comprise set screws 21 which are threaded through the top of the latter so as to engage the respective butt shanks 17 of said looper devices. In order to permit the 55 use of screws of substantial size and strength, and, in such case to provide clearance between adjacent screws, said set screws are preferably arranged in two parallel lines, with those of one line in staggered relation to those of the other line.

When a comparatively large number of looper devices are mounted in the carrier block 10, the top wall of the latter may be suitably reenforced and secured against upward springing or yielding to the thrust of the tightened set screws 21. 60 To this end reenforcing and supporting shim members 22, preferably in the form of washers, corresponding in thickness to the height of the socket channel 12, are inserted within the latter adjacent to each end thereof and outwardly of the 65 gang of looper devices. Engaged through the top wall of the socket channel 12 and through the shim members 22 are fastening or binding screws 23 which are screwed tightly home into the body of said carrier block 10, thus firmly ty-

ing or anchoring the top wall of the socket channel 12 to the main body of the carrier block against any substantial spring of yielding displacement relative to the top faces 19 of the inserted butt shank portions 17 of the looper devices. If the gang of looper devices employed is of comparatively small number, said shim members 22 and screws 23 may be omitted.

It will be understood by those skilled in the art, that when the multiple looper means is operatively incorporated in a sewing machine, each looper device will cooperate with a corresponding reciprocable needle 24 included in a gang of the latter corresponding in number to the number of looper devices, whereby oscillation of the looper means in the well known manner relative to the reciprocation of the thread carrying needles will hold, release and draw into interlooped relation the threads so as to produce the familiar chain stitch (see Fig. 6).

The character of the work produced is shown in Fig. 7, wherein suitably spaced lines or runs 25 of stitching are simultaneously produced.

It will be obvious that some changes in and apparently widely different embodiments of this invention could be made without departing from the scope thereof as defined in the following claims. It is therefore intended that all matter contained in the foregoing description or shown in the accompanying drawing shall be interpreted as illustrative and not in a limiting sense.

I claim:

1. A multiple looper means for sewing mechanism comprising, a carrier block having an outwardly open horizontal socket channel bounded by opposed spaced walls, one wall providing a flat seating surface and the other wall having therein laterally spaced transverse seating grooves of arcuate cross section, a plurality of looper devices having butt shank portions for insertion in said socket channel, said butt shank portions having flat faces to oppose said flat seating surface of the one wall of the socket channel and rounded faces to fit in said seating grooves of the other wall of the socket channel, and means to secure said butt shank portions against outward displacement from said socket channel.

2. A multiple looper means for sewing mechanism comprising, a carrier block having an outwardly open horizontal socket channel bounded at one side with a flat seating surface and provided on its opposite side with laterally spaced transverse seating grooves of arcuate cross section, a plurality of looper devices having butt shank portions for insertion in said socket channel, said butt shank portions having flat faces to oppose said flat seating surface of the socket channel and rounded faces to fit in said seating grooves of the socket channel, means to secure said butt shank portions against outward displacement from said socket channel, shim members fitted into the end portions of said socket channel outwardly of the looper devices, and anchoring means cooperative with said shim members.

3. A multiple looper means for sewing mechanism comprising, a carrier block having an outwardly open horizontal socket channel bounded at its top side with a flat seating surface and provided in its bottom surface with laterally spaced transverse seating grooves of arcuate cross section, a plurality of looper devices having butt shank portions for insertion in said socket channel, said butt shank portions having flat top

faces to oppose said flat seating surface of the socket channel and rounded bottom faces to fit in said seating grooves of the socket channel, said looper devices having stop shoulders offset from the butt shank portions to engage the front face of said carrier block to determine the exterior projecting positions of said looper devices relative to said carrier block, and means to secure said butt shank portions against outward displacement from said socket channel.

4. A multiple looper means for sewing mechanism comprising, a carrier block having an outwardly open horizontal socket channel bounded by opposed spaced top and bottom walls, the top wall providing a flat seating surface and the bottom wall having therein laterally spaced transverse seating grooves of arcuate cross section, a plurality of looper devices having butt shank portions for insertion in said socket channel, said butt shank portions having flat top faces to oppose said flat seating surface of the socket channel top wall and rounded bottom faces to fit in said seating grooves of the socket channel bottom wall, said looper devices having stop shoulders offset from the butt shank portions to engage the front face of said carrier block to determine the exterior projecting positions of said looper devices relative to said carrier block, and a set screw cooperative with each looper device, said set screws being threaded down-

wardly through said carrier block to engage the flat top faces of said butt shank portions of said looper devices.

5. A multiple looper means for sewing mechanism comprising, a carrier block having an outwardly open horizontal socket channel bounded at its top side with a flat seating surface and provided in its bottom surface with laterally spaced transverse seating grooves of arcuate cross section, a plurality of looper devices having butt shank portions for insertion in said socket channel, said butt shank portions having flat top faces to oppose said flat seating surface of the socket channel and rounded bottom faces to fit in said seating grooves of the socket channel, said looper devices having stop shoulders offset from the butt shank portions to engage the front face of said carrier block to determine the exterior projecting positions of said looper devices relative to said carrier block, a set screw cooperative with each looper device, said set screws being threaded downwardly through said carrier block to engage the flat top faces of said butt shank portions of said looper devices, shim members fitted into the end portions of said socket channel outwardly of the looper devices, and fastening screws extending through said carrier block and shim members for the purposes described.

ANTON KIERNER. 30
